UNITED STATES PATENT OFFICE.

ALFRED B. LEEPER, OF OWANECO, ILLINOIS.

BAND-CUTTER PLATFORM FOR THRASHING-MACHINES.

SPECIFICATION forming part of Letters Patent No. 402,258, dated April 30, 1889.

Application filed August 14, 1888. Serial No. 282,698. (No model.)

To all whom it may concern:

Be it known that I, ALFRED B. LEEPER, of Owaneo, in the county of Christian and State of Illinois, have invented a new and Improved Band-Cutter Platform for Thrashing-Machines, of which the following is a full, clear, and exact description.

My invention relates to an improvement in band - cutter platforms for thrashing - machines, and has for its object to provide a means whereby a platform of simple and durable construction may be conveniently and expeditiously attached to the wheel of the machine or the wagon carrying the machine, whereby the person cutting the bands of the grain may be provided with a firm and comfortable support.

The invention consists in the construction and combination of the several parts, as will be hereinafter fully set forth, and pointed out in the claim.

Reference is to be had to the accompanying drawings, forming a part of this specification, in which similar letters of reference indicate corresponding parts in all the figures.

Figure 1 is a partial side elevation of a thrashing - machine illustrating the application of my improved platform. Fig. 2 is a partial end view of the machine, the platform being partially in section; and Fig. 3 is a vertical section on line $x-x$ of Fig. 2.

In carrying out the invention, A represents a truck upon which the thrashing-machine A' is mounted, which truck is provided with suitable axles and wheels, A², mounted upon said axles. The platform B consists, preferably, of a rectangular body, B', which may consist of a single board or a number of boards attached together in any suitable manner.

Upon the bottom or under side of the body or platform B' two spaced transverse brace-bars or beams, C and C', are respectively secured. The beam or brace-bar C' is provided upon the under face with a concaved or semi-circular recess, d, which recess is adapted to conform to the contour of the wheel-tire.

Through the body, and also centrally

through the recessed bar C', a clamping-bolt, d', is projected, the upper end whereof is 50 threaded and provided with a nut, d², the lower end being curved to form a hook, d³, adapted to engage the wheel-felly, as shown in Fig. 2.

At or about the center of the cross bar or 55 beam C a brace-bar, D, is hinged, adapted, when not in use, to fold up beneath the body parallel therewith.

In operation the nut d² of the clamping-bolt d' is loosened and the hook-shaped portion d³ of the said bolt is passed beneath the felly of the wheel adjacent to the feed-table D' of the thrashing - machine, and the concaved surface of the bar C' is made to rest upon the upper surface of the wheel-tire, as 65 best shown in Fig. 3, and the said beam is clamped to the said wheel by screwing down the nut d² to a firm contact with the upper surface of the table. The outer end of the platform or body is supported through the 70 medium of the hinged bar D, the free end of which bar is made to rest upon the hub of the wheel and bear against one of the spokes secured therein. To that end the brace-bar D is preferably provided with a recess to accommodate the said spoke.

By the construction above described I provide a platform which may be quickly and firmly attached to one of the wheels of a 75 thrashing-machine truck.

Having thus described my invention, what I claim as new, and desire to secure by Letters Patent, is—

An improved platform for attachment to the wheeled truck of a thrashing-machine, 85 the same consisting of the flat body having near one end a concavity adapted to fit the rim of a wheel, the hook - shaped clamping-bolt applied to such recessed end of the body, and a brace-bar hinged to the under side of 90 said body near its outer end, substantially as shown and described.

ALFRED B. LEEPER.
